UNITED STATES PATENT OFFICE.

ATTO LENTSCH, OF SCHÖNINGEN, GERMANY.

CENTRIFUGAL CREAMER.

SPECIFICATION forming part of Letters Patent No. 507,442, dated October 24, 1893.

Application filed November 30, 1892. Serial No. 453,681. (No model.) Patented in France September 5, 1892, No. 224,134, and in England October 5, 1892, No. 17,707.

To all whom it may concern:

Be it known that I, ATTO LENTSCH, a subject of the Duke of Brunswick and Emperor of Germany, residing at Schöningen, Brunswick, Germany, have invented certain new and useful Improvements in Centrifugal Creamers, of which the following is a specification, this invention having been patented to me in France September 5, 1892, No. 224,134, and in England October 5, 1892, No. 17,707.

My invention relates to centrifugal machines for liquids and the object of my invention consists in pipes which I arrange in the drum of centrifugal machines, which increase the pressure surface for the liquid, and separate the bulk of the liquid into a large number of thin columns. I attain this object by the mechanism illustrated in the accompanying drawings, in which—

Figure 1, is a vertical section of a centrifugal drum, and Fig. 2, is a plan in section of Fig. 1. Fig. 3, is a vertical section of a centrifugal drum, in which the pipes are arranged one inside the other, and Fig. 4, is a sectional plan of Fig. 3. Fig. 5, is a vertical section of a centrifugal drum, in which the liquid enters from the top and leaves at the bottom. Fig. 6, is a vertical section of a centrifugal drum, in which the liquid enters through special inlets.

A, is the drum of a centrifugal machine which is rotated by the shaft w. (In the drawings the shaft w, is broken off.) In the drum A, are placed tubes B, B, in concentric circles. The pipes B, B, are fastened in the drum by providing the outer pipes with holes d, so as to receive studs s, riveted to the drum. The inner pipes may be pressed against the outer ones by means of one or more tension rings or also by a pipe placed in the middle. The pipes B, B, are so arranged that the liquid can enter at one end and leave at the other end thereof. For this purpose the said pipes are furnished at their inlet with holes, recesses, slots or the like, or may be cut angular to their axis.

To prevent the separated light and heavy parts mixing on leaving, the outlet surfaces may be relatively displaced, so that the jets

pass below or over each other, while otherwise they would pass by the side of each other. The liquid moves in the direction as indicated by the arrows.

The liquid to be set in motion enters the drum through the pipe z. At b, the liquid enters the pipes B, and at c, it leaves again the pipes separated into light and heavy liquid. The light liquid passes to the middle, where the movement is the least and leaves the drum through the outlet pipe r. The heavy liquid passes to the circumference of the drum and leaves it through the outlet pipe m.

In the Figs. 3 and 4 is shown a drum with one row of pipes only, the surface of which is increased with pipes, ribs, partitions and the like. In the pipe B—f, are inserted eight small pipes and in the pipe B—g, three larger ones, which support each other. In the pipe B—h, one pipe and one partition is inserted, in the pipe B—i two pipes, each with projecting ribs, so that the inner pipes are positioned eccentrically to the outer one. In the pipe B—k, is inserted concentrically a pipe which is supported by four semicircular conduits. In the pipe B—l, is inserted an oval pipe, in the pipe B—o, three sided prisms. In the pipe B—p are pipes with ribs inserted. It will be understood that I have shown only a few of the many combinations, which facilitate the increase of the surface of the pipes.

In Fig. 5, is shown the drum of the centrifugal machine, by which the inlet of the liquid is at the top and the outlet below, while in the foregoing figures are shown drums with the inlets below and the outlet at the top. A, is the drum, w, the shaft, l, the stuffing-box. B, B, are pipes in the drum.

In order to facilitate the entrance of the liquid in the pipes B, B, I give them lateral openings 30, the mouths of which are directed toward the middle of the drum A, as shown in Fig. 6.

The liquid to be set in motion takes its way through the drum as the arrows indicate. It enters by the pipe z, and fills the drum and with it the pipes B. The centrifugal force separates the liquid into light liquid which

leaves the drum at the outlet *m*, and into heavy liquid, which leaves the drum at the outlet *r*.

What I claim is—

5 1. In a centrifugal creamer, the combination of a rotating drum *A*, and a series of pipes *B*, located within the drum having open bottoms and tops with inlet and outlet passages at opposite ends of the drum, substantially as described.

10 2. In a centrifugal creamer, the combination of a rotating drum *A*, a series of pipes *B*, within the same having open bottoms and tops, an inlet at one end of the drum and two outlets leading from different points in rela-

tion to the center of the machine, and at the end thereof opposite the inlet, substantially as described.

15 3. In a centrifugal creamer, the drum *A*, and a series of open ended pipes *B*, arranged in successive rows of varying lengths, said drum having an inlet at one end and an outlet at the other end, substantially as described.

In testimony that I claim the foregoing as my invention I have signed my name in presence of two subscribing witnesses.

ATTO LENTSCH.
